UNITED STATES PATENT OFFICE.

BENJAMIN LEVY, OF SCHENECTADY, NEW YORK.

FOOT-EXERCISING DEVICE.

Application filed June 26, 1922. Serial No. 570,815.

To all whom it may concern:

Be it known that I, BENJAMIN LEVY, a citizen of the United States, residing at Schenectady, New York, have invented certain new and useful Improvements in a Foot-Exercising Device, of which the following is a specification, reference being had therein to the accompanying drawings.

This invention comprises a foot exercising device. It is contemplated, among the objects of the invention, to provide a simple and practical apparatus which will readily lend itself to a large variety of movements and adjustments to accommodate various sizes of feet and various forms of movements. More specifically, it comprises a device for use in connection with a system of resistant exercises used in the prevention and cure of weakened muscles of the human foot.

It is further contemplated to provide means which will permit only inversion and dorsal flexion of the feet when used in one way, and which will also provide instrumentalities which will be used only for plantar flexion, the two sets being arranged compactly in operative relation to an adjustable and universally movable heel rest; to provide a device wherein means are included for setting up on a dial or the like the amount of resistance overcome in the use of the exercising device; and wherein the different elements are compactly arranged, the device forming a neat and practical apparatus for the purposes set forth.

Other objects and advantages will in part be apparent and in part be brought out more fully in the description which follows.

An embodiment of the invention is illustrated in the accompanying drawings, the following views being shown:

Fig. 1, is a view in top plan, of a device embodying my invention;

Fig. 2, is a view in front elevation of the same;

Fig. 3, is a view in top plan, the top and certain portions being removed, and other portions in section;

Figs. 4, 5, and 6, are detail views, in vertical section, illustrating the arrangement of a securing element, a device for plantar flexion exercise, and a heel rest, respectively.

In these views 1 designates a base or support. It is in the form of a box, having top, bottom, and side sections joined together to form a compartment and all suitably mounted on feet which are preferably made

of some anti-slipping material which will tend to keep the device in set position when in use.

Connecting the top and bottom sections and securing them together, there are bolts 2, three being here shown. Two of these are disposed toward the side extremities of the box, and are provided, on the inside of the box, with wheels or pulleys 3, as best seen in Fig. 4. The bolts which carry these pulleys are bored to form an oil duct leading from outside the box to the outer surface of the bolt, which surface is made smooth to form a bearing for the pulleys.

Upon the third bolt, which is disposed centrally on the other side of the box, there is mounted resistance instrumentality 4, in the form of coil springs, each spring having an end loop disposed around the bolt inside the box, and connected, at its other end, with a cable 5. This cable passes around a pulley and through an opening 6 in the top of the box, there being one cable for each bolt. On the outside of the box the end of each cable carries a stirrup into which the foot is adapted to be placed, as shown in Fig. 1.

In the top and bottom sections there are aligned slots 7, metal reinforced on the surfaces of the box and forming guideways for adjustable posts or supports 8. Each post has a collar 9, extending out over the metal reinforcement on the top of the box, and an adjusting screw 10, provided with a similar collar, engaging the metal reinforcement on the bottom of the box. At the upper portion, each post is provided with a socket in which is disposed a ball 11, on a stem which carries a heel-rest 12. This is padded suitably and shaped to conform to the human heel, the adjustment and mounting permitting free movement in all directions.

The heel rests are spaced apart as shown in Fig. 1, and the stirrups arranged so that the initial position will be as indicated in that figure and the movement of the feet toward each other. Disposed centrally between the heel rests there is an obstruction 13, having a rounded upper surface, and mounted on the top of the box. It is made preferably of wood or iron and is adapted to engage the bottom of the foot at the extremity of its inward movement, causing dorsal flexion of the foot on the leg.

Means are provided for indicating the amount of resistance overcome and this is graduated to set this forth in accordance

with the condition of the muscles. As here shown, and best seen in Figs. 1 and 3, there is secured to each cable, an arm 14 having at one end a pointer 15. This is bent upwardly and extends out through a slot in the upper surface of the box. There is one slot for each cable and in alignment with its corresponding cable. Associated with each slot there is a graduated plate 16, with indications thereon as to the strength required to overcome the tension of the springs, and when the stirrups are moved, the cable pulls the pointer along the graduations on the plate.

15. Means are provided for use in the exercise of the plantar muscles of the feet, and as here shown comprise knobs or buttons 17, placed on either side of the obstruction 13, and at a point where they may be grasped 20 by the toes when the heel is disposed in the heel rest, there being one for each foot. These knobs are detachably arranged on the end of a link 18 which passes through an opening in the top of the box, the other end 25 of the link being connected to a coil spring 19, suitably secured to the bottom of the box. Each button has its individual coil, and it is intended to have buttons of various sizes, interchangeable for use with feet of different 30 sizes. The buttons are grasped by the toes and drawn upwardly, the movement producing contraction of the plantar muscles, or plantar flexion.

35. While the invention has been disclosed in the embodiment herein illustrated, it will be understood that I do not wish to be limited to the precise form of this disclosure as many changes in the construction and arrangement of the parts are considered 40 as within the scope of the invention as set forth in the claims.

What I claim is:

45. 1. A foot-exercising device comprising a support; a heelrest movably mounted on the support; a stirrup for association with a foot to be exercised; a spring resistance instrumentality operatively connected with the stirrup; and an obstruction placed in operative relation to the heel-rest, to be engaged by the foot at a certain point in its movement.

55. 2. The structure set forth in claim 1; and means for producing exercise of the plantar muscles of a foot, said means including and object to be grasped by the toes; and means associated with the object for setting up resistance to the movement of the object.

60. 3. A foot exercising device comprising a support; a spring member secured at one end to the support; a cable associated with the spring member at one end and passing through an opening in the support; a stirrup on the cable; and a heel rest mounted for universal movement in operative relation to the stirrup.

4. A foot exercising device comprising a base; a heel rest supporting device adjustably mounted on the base; a heel rest movably mounted on the supporting device; a stirrup for connection to a portion of a 70 foot to be exercised, when the heel of the foot is disposed in the heel rest; resistance instrumentality operatively associated with the stirrup; and means for producing dorsal flexion of the foot, associated with the heel 75 rest and stirrup.

5. A foot exercising device comprising a base; a heel rest supporting device adjustably mounted on the base; a heel rest movably mounted on the supporting device; a 80 stirrup for connection to a portion of a foot to be exercised, when the heel of the foot is disposed in the heel rest; and means for producing dorsal flexion of the foot, associated 85 with the heel rest and stirrup; said means including an obstruction having a rounded portion and placed in position to be engaged by a portion of the foot to be exercised when the foot is moved in relation thereto.

90. 6. A foot exercising device comprising a base; a heel rest supporting device adjustably mounted on the base; a heel rest movably mounted on the supporting device; a stirrup for connection to a portion of a foot 95 to be exercised, when the heel of the foot is disposed in the heel rest; resistance instrumentality operatively associated with the stirrup; means for producing dorsal flexion of the foot, associated with the heel 100 rest and stirrup; and means for producing exercise of the plantar muscles of the foot 105 operatively associated with the heel rest and stirrup.

110. 7. A foot exercising device comprising a base; a heel rest supporting device adjustably mounted on the base; a heel rest movably mounted on the supporting device; a stirrup for connection to a portion of a foot to be exercised, when the heel of the foot is disposed in the heel rest; resistance instrumentality operatively associated with the stirrup; means for producing dorsal flexion of the foot, associated with the heel 115 rest and stirrup; and means for producing exercise of the plantar muscles of the foot 120 operatively associated with the heel rest and stirrup; said means including a placed object to be grasped by the toes of the foot to be exercised and means for setting up resistance to the movement of the object.

125. 8. A foot exercising device comprising a base; a heel rest supporting device adjustably mounted on the base; a heel rest movably mounted on the supporting device; a stirrup for connection to a portion of a foot to be exercised, when the heel of the foot is disposed in the heel rest; resistance instrumentality operatively associated with the stirrup; means for producing dorsal flexion 130

of the foot, associated with the heel rest and stirrup; means for producing exercise of the plantar muscles of the foot operatively associated with the heel rest and stirrup; said means including a placed object to be grasped by the toes of the foot to be exercised and means for setting up resistance

to the movement of the object; said means including a tension element operatively associated with the object and base. 10

In testimony whereof I affix my signature.

BENJAMIN LEVY.
